No. 37,479.

Patented July 11, 1905.

UNITED STATES PATENT OFFICE.

GEORGE E. SCHWEIG, OF NEW YORK, N. Y.

DESIGN FOR A BUTTON-RIM.

SPECIFICATION forming part of Design No. 37,479, dated July 11, 1905.

Application filed May 11, 1905. Serial No. 260,045. Term of patent 3½ years.

To all whom it may concern:

Be it known that I, GEORGE E. SCHWEIG, a citizen of the United States, and a resident of the city of New York, borough of Manhattan, in the county and State of New York, have invented a new, original, and ornamental Design for a Button-Rim, reference being had to the accompanying drawing, in which the figure is a plan view of a button-rim, showing my new design.

I claim—

The ornamental design for a button-rim, as shown.

GEORGE E. SCHWEIG.
